UNITED STATES PATENT OFFICE

2,547,807

TENONER

Elmer H. Bryant, Oklahoma City, Okla., assignor
of one-half to Cyril Woodrow Bryant, Okla-
homa City, Okla.

Application May 5, 1948, Serial No. 25,249

2 Claims. (Cl. 144—203)

1

My invention relates to tenoners and an object of my invention is to provide a tenoner adapted to overcome the disadvantage inherent in the tenoners known and used heretofore. These tenoners were of complicated construction and in consequence so expensive that the owners of small carpenter and cabinet maker shops could not afford to use them. Furthermore, these tenoners were not adapted to be used in the field and on the job.

An object of my invention therefore is to provide a tenoner of simple construction which is portable so that it can be used in the field on a job, but at the same time is adapted to be mounted on a stationary stand to be used in a shop.

Another object of my invention is to provide a tenoner adapted to be adjusted to form tenons of any desired thickness on boards of any thickness.

A further object of my invention is to provide a tenoner of the character indicated above adapted to support boards of predetermined length and to feed them to the cutting bits to form tenons of predetermined length.

A still further object of my invention is to provide a tenoner of the character indicated above adapted to be adjusted for relishing a finished tenon.

Other objects of my invention not specifically mentioned may appear in the following specification describing it with reference to the accompanying drawing illustrating a preferred embodiment of my invention. It is, however, to be understood, that my invention is not to be limited or restricted to the exact construction and combination of parts described in the specification and shown in the drawing, but that such changes and modifications can be made which fall within the scope of the claims appended hereto.

In order that my invention may be better understood, I will now proceed to describe it with reference to the accompanying drawing, in several figures of which similar parts are designated by similar reference characters and in which

Figure 1 is a view in top plan of a tenoning machine constructed in accordance with the present invention.

Figure 2 is a view in side elevation of the same.

2

Figure 3 is a view in elevation of the front end of the machine.

Figure 4 is a vertical transverse section taken substantially on the line 4—4 of Figure 2 showing one position of the stop lever and associated parts.

Figure 5 is a view corresponding to Figure 4 and showing another position of the stop lever and associated parts.

10 Figure 6 is a view in perspective of a board having a tenon formed thereon.

Figure 7 is a view in perspective showing the board tenon having a relish formed thereon.

The tenoner embodied herein comprises a machine bed B having a working table 10 of substantially rectangular form. In the front edge portion of the working table, a curved cut-out is provided in order to facilitate the manipulating of a slide S to be described later. On the left-hand end portion of the working table an angle iron forming a track 11 is secured, the forward end of which is arranged flush with the front edge of the working table, and the rear end portion of which extends beyond the rear

20 edge of said table. On the right hand end portion of the table 10, a guide rail 12 is secured by means of a plurality of screws a. This guide rail is formed by an angle iron, one leg of which rests on the working table so that its edge is arranged flush with the right hand edge of the table and that its other leg extends upwardly therefrom. The guide rail 12 extends a comparatively long distance beyond the rear edge of the working table. From the right hand edge of the table a bar-like support member 13 extends to the right and is arranged with its rear surface flush with the rear edge of the table. Adjacent the rearmost end of the guide rail 12, a plate like bracket 14 is secured to the horizontal leg of the rail angle by means of a plurality of bolts. This plate bracket extends horizontally toward the right and an electric motor 15 or the like is rigidly mounted on said bracket. On the end portion 16 of the motor shaft 17 pointing toward

30 the left, a grooved driving sheave 18 is rigidly mounted.

35 A machine head H having a substantially right angle cross section comprises a horizontal base portion 19 and a body portion 20 extending substantially vertically upward from said base por-

40

45

50

tion. In the forward portion of the body an arcuate slot 21 is provided extending substantially upwardly and downwardly and so that the concave edge of the slot faces rearwardly, and toward the rear edge of the body a similar arcuate slot 22. A pair of spaced supports 23, one disposed in a plane below the other, are mounted on the body 20 for independent vertical positioning and different angular relationships, and have cylindrical housings 24 and 25 extending horizontally therefrom in parallel relation over the base portion 19. In each cylindrical housing, a cutter arbor 26 is rotatably supported by means of ball bearings or the like (not shown). The cylindrical housings are arranged with respect to each other so that the shanks of the arbors extend freely through the arcuate slots 21 and 22 respectively in the body. On the end of each arbor shank, a sheave 27 is rigidly mounted and an idler sheave 28 is rotatably mounted on a shaft bolt 29 secured in and extending outwardly or to the right of the body 20 so that the idler sheave is located somewhat above and in front of the rear sheave 27. The machine head H is mounted on the support member 13 and the plate bracket 14 by means of bolts 30 extending through the base portion 19. The driving sheave 18, the two arbor sheaves 27 and the idler sheave 28 are arranged in a common plane alignment with each other so that a belt 31 can be trained over the idler sheave, the rear arbor sheave, the front arbor sheave and back to the driving sheave in such a manner that the two arbor sheaves are rotated in opposite directions. On the front end portion of each arbor, a multiple cutting bit 32 is securely but exchangeably mounted. In order to reinforce the machine bed B, a reinforcing member 33 consisting of an angle iron or the like extends between and is fastened to the rear end portion of the angle iron 11 and the rail 12.

The above mentioned slide S or carriage has substantially the shape of a right angled triangle. The hypotenuse 34 is preferably made from a flat bar, on the right hand end of which a guide member 35 is secured in any desired conventional manner. This guide member has preferably a cross section shaped like an inverted V and slidably engages the upper edge of the angle forming the guide rail 12. The other side of the right angled slide S is formed preferably by an angle iron 36 welded or otherwise secured with its right hand end portion to the forward end portion of the guide member. The angle iron 36 is securely connected with the left hand end portion of the hypotenuse 34 and extends toward the left beyond this connection as shown at 37.

A wheel or roller 38 is rotatably secured under the junction of the hypotenuse 34 and the angle iron 36, so that the plane surface of the slide S is arranged parallel to the axis of the cutter arbors 26 when the slide is arranged on the machine bed B in working position, that means so that the guide member 35 is located slidably on the guide rail 12 and that the roller 38 can travel on the track 11. To reinforce the slide S and to improve the supporting capacity thereof, a plurality of intermediate members 39 are arranged between the hypotenuse 34 and the angle iron 36 and are spaced from each other and extend parallel to the guide member 35.

A pair of curved adjusting slots 40 are provided in the body 20 in spaced parallel relation with respect to each of the slots 21 and 22. An adjusting bolt 41 is mounted in each of the sup-

ports 23 and extends through adjacent ones of the slots 40. Both of the supports 23 are each pivotally mounted on a bolt 41' passing through the end thereof opposite from the bolt 41 and secured in the body 20. On the bolt extending through adjacent ones of the slots 40, for the right hand support 23, a locking lever 42 is threaded and is adapted to force a washer 43 on the bolt into clamping engagement with the body 20. The adjusting bolt 41, for the left hand support 23 (Figures 4 and 5) is provided with a nut and a washer (not shown) only for securing the same in any of its positions of adjustment.

When a tenon 44 is to be formed on a board 45, it is placed onto the slide S so that one side edge abuts the upright leg of the angle iron 36 forming one side of the triangular slides. Then the locking lever 42 is pivoted to loosen the grip of the washer on the body, and the arbor housing 23 is adjusted with the help of the lever 42 in the desired working position. That means the arbors 26 are moved in their respective slots 21 and 22 until the vertical distance between the lowermost cutting edge of the cutting bit 32 on the raised arbor and the uppermost cutting edge of the bit secured to the lowered arbor is equal to the desired thickness of the tenon to be produced. The arbor housing is then secured in this position by tightening the grip of the washer on the body by pivoting the adjusting lever into locking position. In order to facilitate the cutting of tenons of equal length on boards of a certain length, an adjustable stop 46 is slidably mounted on the angle iron 36 and is adapted to be secured in adjusted position by any conventional means, for instance, by means of a clamp bolt 47 or the like. The stop may consist of a clip angle located inside the angle iron 36 and an off-set plate 48 secured to the stop angle and extending downwardly on the outside of the upper right leg of the angle iron 36.

After the board to be tenoned is placed in position on the slide so that the end to be worked extends the predetermined distance over the slide, the motor is started and the slide is moved back and forth on the machine bed, so that the cutting bits will form a tenon of the desired thickness and length.

When a relish 50 is to be formed on the tenon, the lever 42 is pivoted to release the washer 43. The right hand support 23 is adjusted so that one cutting bit is disposed at the same level as the finished tenon. A stop screw 51, carried by a bracket 51' mounted on the outer side of the body 20 is provided to limit the movement of a lever 52, rigidly pivotally mounted on the said support, to facilitate the positioning of the latter relatively to the other, or left hand support. The slide S is moved to force the edge of the tenon against the cutting bit to form the relish.

The above described tenoner may be mounted on a stand of any preferred construction to be used as a relatively stationary machine in a shop, or may be secured to a portable support construction of any preferred and convenient kind for the use on a job in the field.

I claim:

1. In a tenoner, a main vertical support, a pair of horizontally spaced supporting elements pivotally mounted on one side of said main support, one of said elements being in a plane slightly below the other, an arbor journaled in each of said elements and extending through the same and said main support, a cutting bit mounted on the outer end of each of said arbors, means for

securing said elements in different angular relationships, and power driven means interconnecting the inner ends of said arbors for imparting rotary motion to the same and said cutting bits.

2. The invention as defined in claim 1, with a flat elongated base having said main support rising transversely thereof toward one of its ends, a bracket mounted at the said one end of said base, an electric motor operatively connected with said driven means, a work supporting slide mounted on said base and movable thereon relatively to said cutting bits, and adjustable means on said slide to buttress work pieces of different sizes during cutting operations thereon. 10 15
